WAVE TRANSMISSION CIRCUITS

Walter van B. Roberts, Princeton, N. J., assignor to Radio Corporation of America, a corporation of Delaware

Original application September 30, 1936, Serial No. 103,230. Divided and this application September 29, 1937, Serial No. 166,248

2 Claims. (Cl. 178—44)

My present invention relates to electrical wave transmission networks, and more particularly to high frequency networks of the filter type employing electronic coupling devices. This application is a division of my co-pending application Serial No. 103,230, filed Sept. 30, 1936, now Patent No. 2,184,400, December 26, 1939.

The main object of this invention is to provide a wave filter utilizing electronic devices upon whose transconductances and/or transimpedances the cut-off frequencies and the attenuation of the filter depends.

Such a filter possesses the important advantage over filters of known types that the behavior of the filter may be controlled by biasing potentials for the electronic devices. By suitably adjusting the biasing potentials of the electronic devices not only can the transmitting range of the filter be altered at will, but also the gain, or, if desired, the attenuation of the filter may simultaneously and independently be adjusted. Since the variation of biasing potentials requires substantially no power, the filter characteristics may be automatically controlled in accordance, for example, with the strength of the signals traversing the filter. While these filters differ from ordinary filters in that there is no reactive coupling between elements, their use is subject to the same considerations and will be readily understood by one skilled in the art of wave filters.

The novel features which I believe to be characteristic of my invention are set forth in particularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings:

Fig. 1 shows schematically a filter section utilizing reactance elements, transconductances and transimpedances which are dissimilar,

Fig. 2 shows a high pass filter section utilizing similar reactance elements and a pair of screen grid tubes as transconductances,

Fig. 3 shows a band pass filter section utilizing similar reactance networks, and a pair of screen grid tubes so connected as to perform the functions of transimpedances,

Fig. 4 shows a band pass filter employing similar reactance networks and a pair of transconductances,

Fig. 5 shows an element of a section of a band pass filter adapted to have increased uniformity of iterative admittance over a large portion of the transmitting band, and a high degree of relative attenuation at a pair of frequencies on either side of the band, and

Fig. 6 shows a receiving system embodying band pass filters constructed in accordance with the invention.

Referring now to Fig. 1, there is shown a four terminal network terminated by an impedance k . The shunt elements Z_1 and Z_2 are pure reactance networks of any nature. The dotted rectangle Y represents transconductance devices carrying out the following function: A positive potential e_1 at the left side of Y causes current $e_1 y_{12}$ to flow into the rectangle from the right without any corresponding flow outward from the left. At the same time a positive potential e_2 , on the right side of Y causes current $e_2 y_{21}$ to flow out of the rectangle from the left. In a similar manner rectangle Z represents transimpedance devices; that is, devices for introducing into a circuit a voltage proportional to current in another circuit, without reaction of any sort on the first circuit. In the diagram where z_{12} is the voltage induced in Z_2 by unit current in Z_1 , and z_{21} is the voltage induced in Z_1 by unit current in Z_2 , the arrows within the rectangle indicate the direction of the voltages induced when the directions of the currents are as shown by the solid headed arrows.

The iterative impedance k of the four terminal structure is found as in the case of an ordinary filter section; by solving for the input impedance e_1/i_1 with k considered as an arbitrary terminating impedance, and then equating this input impedance to k . This equation defines k . Having found k , the current or voltage ratio per section of a filter terminated by its iterative impedance k is found by calculating the ratio e_2/e_1 or i_2/i_1 , and substituting in the expression for either of these ratios the value of k already found. The carrying out of the calculation above outlined is simple but tedious, and it will be sufficient here to note that as a result there is secured the following:

$$k = \frac{\frac{Z_1 - Z_2}{2} \pm \sqrt{\left(\frac{Z_1 - Z_2}{2}\right)^2 + [Z_1 Z_2 + z_{12} z_{21}] \{1 + y_{12} z_{21} + y_{21} z_{12} + y_{12} y_{21} z_{12} z_{21} + y_{12} y_{21} Z_1 Z_2\}}}{\{1 + y_{12} z_{21} + y_{21} z_{12} + y_{12} y_{21} z_{12} z_{21} + y_{12} y_{21} Z_1 Z_2\}} \quad (\text{Eq. 1})$$

$$\frac{e_2}{e_1} = \frac{(Z_1 Z_2 + z_{12} z_{21}) y_{12} + z_{12}}{\frac{Z_1 + Z_2}{2} + \sqrt{\left(\frac{Z_1 + Z_2}{2}\right)^2 + [(Z_1 Z_2 + z_{12} z_{21}) y_{12} + z_{12}] \{(Z_1 Z_2 + z_{12} z_{21}) y_{21} + z_{21}\}}} \quad (\text{Eq. 2})$$

Now since both Z_1 and Z_2 are pure reactances, the first term in the denominator of Equation 2 is pure imaginary. On the other hand, all the quantities under the radical sign of Equation 2 are real. Hence, for all values of Z_1 and Z_2 which make the quantity under the radical a positive real, the denominator of Equation 2 consists of an imaginary term plus a real term, and the absolute value of the denominator is the square root of the sum of their squares. If Equation 2 is by the method reduced to its absolute value it becomes:

$$\frac{e_2}{e_1} = \sqrt{\frac{(Z_1 Z_2 + z_{12} z_{21}) y_{12} + z_{12}}{(Z_1 Z_2 + z_{12} z_{21}) y_{21} + z_{21}}} \quad (\text{Eq. 3})$$

which is the current, or voltage, ratio per section for the range of frequencies specified by requiring the quantity under the radical of Equation 2 to be positive.

In the case of ordinary filters composed of inductances and capacities only, the theoretical filtering action that occurs per section of a filter having an infinite number of sections may be fairly clearly approximated in a filter having only a few sections provided the latter is terminated by a resistance which is preferably taken equal to the value of the iterative impedance of the last filter section evaluated at the mid-frequency of the band in the case of a band filter, or at a very low frequency in the case of a low pass filter, or at a very high frequency in the case of a high pass filter. It will be understood that the same considerations apply in the case of the present invention, and that preferably when the iterative impedance of the filter section (given by Equation 1) is changed the terminating resistance will be correspondingly changed.

To provide a true filter action the ratio given by Equation 3 should be independent of frequencies over a range of frequencies. If y_{12} and y_{21} and z_{12} and z_{21} are each independent of frequency, the ratio is also independent if $y_{12} z_{21} = y_{21} z_{12}$, or if $y_{12} = y_{21} = 0$ or if $z_{12} = z_{21} = 0$. The first of these conditions leads to structures having two transmission bands, or, as a special case, a structure amplifying all frequencies uniformly. The second and third conditions, however, lead to structures much simpler, and of more practical importance, some of which will be described more in detail.

Fig. 2 shows a high-pass structure where $z_{12} = z_{21} = 0$ and $Z_1 = Z_2 = 1/y$. In this case the current ratio per section is simply:

$$\frac{y_{12}}{y + \sqrt{y^2 + y_{12} y_{21}}}$$

which is constant for all frequencies from infinity (where $y = 0$) down to the frequency at which

$$|y| = \sqrt{y_{12} y_{21}}$$

and throughout the range of frequencies so defined has an absolute value

$$\sqrt{y_{12} y_{21}}$$

In this structure the tube 1 providing the transconductance y_{12} may be an ordinary screen grid tube, while the negative transconductance device 2 required to act as y_{21} may be obtained by using a pliodynatron whose plate potential is adjusted to a point of maximum reversed plate current so that the internal plate resistance is extremely high, while the transconductance be-

tween control grid and plate current is negative.

Of course, in any of the filters of the invention any suitable negative transconductance device may be used. In fact, an ordinary tube may be used if means are provided for exciting its grid with voltage proportional to e_2 of Fig. 1, but opposite in phase from e_2 . However, as the particular devices that may be used in the electronic portions of the filter are not part of the present invention, they will be indicated merely symbolically by a circle including a control element and a current electrode. Whatever kind of device is used, means for supplying operating and control voltages, and for blocking off undesired direct current potentials where necessary, will be understood to be supplied in any of the well known ways.

Since the cut-off frequency of the high pass filter of Fig. 2 is determined by the value of

$$\sqrt{y_{12} y_{21}}$$

while the gain per section is

$$\sqrt{y_{12} / y_{21}}$$

this filter may be controlled both as to gain and cut-off by suitable variation of y_{12} and y_{21} . If capacitive admittances are substituted for the inductive admittances y of Fig. 2, the filter becomes a low pass filter, and may advantageously be used in the audio frequency system of a radio receiver where the audio frequency gain and cut-off frequency, or both, are desired to be controlled automatically.

For example, in receiving weak signals accompanied by considerable noise it is desirable to lower the cut-off frequency of the audio system. This may be done automatically by controlling either y_{12} or y_{21} , or both, by a voltage derived from rectification of the incoming carrier. If both y_{12} and y_{21} are varied by similar factors, the gain will remain unaltered. However, if a control voltage developed from rectification of the audio output of the detector is applied to superpose an opposite variation of y_{12} and y_{21} , the band width will not be affected by this superposed variation but the gain will be altered in accordance with the average strength of audio signals. This control may be used either for compressing or expanding the range of audio intensities.

Fig. 3 shows a low impedance band pass filter where $Z_1 = Z_2 = Z$, $y_{12} = y_{21} = 0$, and z_{12} and z_{21} are independent of frequency. Both the tubes 1 and 2 are ordinary screen grid tubes. The voltage on the grid of tube 1 is directly proportional to input current and inversely proportional to frequency, while the induced voltage in the output circuit is directly proportional to plate current of tube 1 and to frequency. Likewise, the voltage on the grid of tube 2 is proportional to output current and inversely to frequency while the voltage induced in the input circuit by the plate current of tube 2 is proportional to its current and to frequency. Hence, the induced voltage in either circuit is proportional to current in the other circuit, and independent of frequency. As a practical matter, to avoid increasing reactive coupling through unavoidable tube capacity, it is advisable to connect the grid of the tube 2 acting as z_{21} across only a fraction of the total capacity reactance of the output branch as shown in Fig. 3. In this case, from Equations 1, 2 and 3 we find

$$k = \sqrt{Z^2 + z_{12} z_{21}}$$

and the current ratio per section is

$$\sqrt{z_{12}/z_{21}}$$

over the band of frequencies where

$$|Z| < \sqrt{z_{12}z_{21}}$$

Z representing the input circuit impedance and also the output circuit impedance as mentioned above.

Fig. 4 shows a high impedance band pass filter where $Z_1 = Z_2 = 1/y$ and $z_{12} = z_{21} = 0$, and ordinary tubes are used. The effect of negative transconductance for y_{21} is simulated by exciting the grid of the tube 2 providing y_{21} with a voltage 180° out of phase with the output voltage by means of a reversing transformer winding 3. In this case the iterative admittance

$$1/k = \sqrt{y^2 + y_{12}y_{21}}$$

and the current, or voltage ratio per section is

$$\sqrt{y_{12}/y_{21}}$$

over the band of frequencies wherein

$$|y| < \sqrt{y_{12}y_{21}}$$

Fig. 5 shows a particular structure that may be substituted for the reactance networks of Fig. 4 to provide a more uniform value of iterative impedance over the transmitted band together with high relative attenuation of frequencies just outside of the band. The high attenuation is obtained by arranging the structure to be series resonant at frequencies just outside the band on either side thereof. The uniform value of $1/k$ is obtained by making the admittance of the structure low relative to

$$\sqrt{y_{12}y_{21}}$$

over most of the band, the approach of resonance at the outlying frequencies, however, insuring that the admittance rises rapidly near cut-off to the value

$$\sqrt{y_{12}y_{21}}$$

which it must have for cut-off. In each of Figs. 2, 3 and 4 there is shown the terminating resistance K across the output terminals of the filter; the manner of choosing the proper termination has been discussed previously.

In Fig. 6 there is shown a superheterodyne type of radio receiver which employs an I. F. amplifier consisting of a two section band pass filter; the filter sections being essentially those of Fig. 4. The amplifier tube 10 has its input electrodes coupled across the resonant input circuit 11, the latter being tuned to the operating I. F. which may be chosen from a range of 75 to 450 k. c. The I. F. energy source may be any desired type of converter, or first detector, network; those skilled in the art are fully aware of the superheterodyne type of construction wherein the I. F. amplifier is preceded by one, or more, stages of tunable radio frequency amplification and a first detector. The resonant circuit 12, tuned to the I. F. is connected between the output electrodes of the amplifier 10. The negative transconductance element of the first filter section comprises the tube 13, whose anode is connected to the high alternating potential side of input circuit 11. The anode of tube 13 is maintained at the desired positive voltage by connecting the low alternating side of input circuit 11 to the source of positive voltage B (not shown). A direct current blocking condenser 14 is connected between the grid of tube 10 and the anode connection to

circuit 11. The cathodes of tubes 10 and 13 are grounded, and initial negative grid biasing sources 15 and 16 furnish the grid biases for tubes 10 and 13 respectively.

5 The input electrodes of tube 13 are coupled to the circuit 12 by means of the reversing transformer 17; the secondary winding 17' of the latter being connected in series, between the grid of tube 13 and the negative terminal of bias source 16, with a pulsating current filter resistor 18. The section comprising circuits 11, 12 and tubes 10, 13 provides a high impedance band pass filter. The grid of tube 13 is excited with a voltage 180° out of phase with the output voltage developed across circuit 12 by virtue of the reversing transformer 17. Hence, there is simulated the effect of negative transconductance between the input and output circuits 11, 12.

The following band pass filter section includes 20 amplifier 19 whose input electrodes are connected across the circuit 12. The negative transconductance element for this second section is provided by tube 20 having its grid connected to the secondary winding 22' of reversing transformer 22. The filter resistor 18' is connected in series

25 between the winding 22' and the negative terminal of bias source 16. The anode of tube 20 is connected to the positive voltage source B through the coil of circuit 12. The output circuit 21 is tuned to the operating I. F., and it is connected between the output electrodes of amplifier 19. The sources 15 and 16 provide the normal negative biases for the grids of tubes 19 and 20 respectively; the cathode of the latter tubes being grounded. The reactances of circuit 12 are one half as large as the reactances of the end circuits 11 and 21 of the filter.

The terminating resistance of the filter comprises the diode rectifiers 24 and 25, the load resistors 24' and 25' thereof, and the audio utilization network. The diode 24 has its anode connected to the high alternating potential side of circuit 21 through the condenser 26. The diode cathode is at ground potential. The load resistor 24' is connected between the electrodes of diode 24, and the audio frequency component of rectified I. F. current is impressed upon the grid of audio tube 30 through condenser 31 connected to the anode side of resistor 24'. The gain of 45 each of amplifiers 10 and 19 is varied automatically by connecting the grids of the amplifiers, through proper pulsating current filter resistors 32, to the "AVC" connection 23' leading to bias source 15. The positive terminal of source 15 is connected to resistor 24' by an adjustable tap element 40. In this way the magnitude of the AVC bias can be selected; the source 15 providing the maximum amplification bias for each amplifier 10 and 19.

60 The diode 25 is connected in reverse manner across circuit 21. Condenser 41 connects the diode cathode to the terminal 42 of circuit 21, whereas the diode anode is grounded. The load resistor 25 is connected between the electrodes of diode 25 and the audio voltage component of rectified current, flowing through resistor 25', is impressed upon the grid of audio tube 50 by condenser 51; the latter connecting the grid of tube 50 to the positive side of resistor 25'. The audio 65 amplifier tubes 30 and 50 are connected in push-pull relation; the manner of connecting the diodes 24 and 25 to circuit 21 making it possible to operate the audio amplifier grids in push-pull from the diode load resistors.

The gain of each of tubes 13 and 20 is auto-

matically varied by connecting the "ABC" lead 23 (these letters designating the automatic band width control circuit) to a desired point on load resistor 25'. The grids of tubes 13 and 20 are connected, through bias source 16, to the adjustable tap element 60, and the latter can be varied to adjust the magnitude of the band width control bias to be impressed on tubes 13 and 20. The source 16 provides cut-off bias for tubes 13 and 20 in the absence of received signal energy. When signal energy is rectified by diode 25, a positive direct current voltage is developed for overcoming the initial cut-off bias due to source 16. The positive bias applied to tubes 13 and 20 increases with signal carrier amplitude increase, and, hence, the transconductance of each tube 13 and 20 increases.

The audio output of the push-pull stage 30-50 may be utilized in any desired manner. For example, one, or more, audio amplifiers may follow, and a final reproducer will terminate the receiver system. The anode side of resistor 24' is preferably connected to control the gain of one, or more, of the signal transmission tubes preceding I. F. amplifier 10. Since the AVC connection to the pre-I. F. stages will furnish effective gain control, the tap 40 can be set at an intermediate point on resistor 24'.

The taps 40 and 60 are related in adjustment in a predetermined manner. In general, the most effective band width control is secured by adjusting tap 60 towards the positive end of resistor 25', and setting tap 40 adjacent the cathode terminal of resistor 24'. This is because of the fact that the band width in the filter depends on the square root of the product of the positive and negative transconductances of the two tubes in each section; whereas the amplification of each section depends on the square root of the ratio of said transconductances. From this it follows that moving tap 60 to the upper end of resistor 25', with similar moving of tap

40 to the lower end of resistor 24', results in an increase in the band widening factor and a decrease in amplification as the signal amplitude increases. The receiver may be operated without any ABC by moving slider 60 to the grounded end of resistor 25'.

However, if freedom of adjustment is desired to secure other relations between band width and amplification, the taps may be permitted to remain independently adjustable. The diodes 24 and 25 may be a tube of the 6H6 type if desired, since the latter comprises a common tube casing housing the electrodes of two diodes. Further, the condensers 26 and 41 may be adjusted in magnitude to maintain a proper impedance match between the filter and its terminating resistance, as the product of the transconductances is varied.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. A wave filter composed of sections each of which consists of a pair of pure reactance networks having positive one-way transconductance therebetween in one direction, and a negative one-way transconductance therebetween in the opposite direction, said filter being terminated by substantially its iterative impedance.

2. A filter as defined in claim 1, wherein each reactance network is arranged to provide rapid cut-off and high attenuations of frequencies close to but outside the transmitted band, and also a substantially constant iterative impedance over the greater portion of the transmitted band.

WALTER VAN B. ROBERTS.
